US00D840956S

(12) **United States Design Patent** (10) **Patent No.:** **US D840,956 S**
(45) **Date of Patent:** ** *Feb. 19, 2019

(54) **PUSH BUTTON**

(71) Applicant: **EATON ELECTRICAL IP GMBH & CO. KG**, Schönefeld (DE)

(72) Inventors: **Artur Wiese**, Bornheim (DE); **Sanan Deepak**, Bonn (DE)

(73) Assignee: **EATON INTELLIGENT POWER LIMITED**, Dublin (IE)

(*) Notice: This patent is subject to a terminal disclaimer.

(**) Term: **15 Years**

(21) Appl. No.: **35/500,724**

(22) Filed: **Oct. 8, 2015**

(80) **Hague Agreement Data**

Int. Filing Date: **Oct. 8, 2015**

Int. Reg. No.: **DM/089656**

Int. Reg. Date: **Oct. 8, 2015**

Int. Reg. Pub. Date: **Mar. 18, 2016**

(51) **LOC (11) Cl.** **13-03**

(52) **U.S. Cl.**

USPC **D13/173**

(58) **Field of Classification Search**

(57)

CLAIM

The ornamental design for a push button, as shown and described.

DESCRIPTION

1. Push buttons

1.1 : Top

1.2 : Perspective

1.3 : Front

1.4 : Right

1.5 : Back

1.6 : Left

1.7 : Bottom

1 Claim, 7 Drawing Sheets
